(57) **CLAIM**

The ornamental design for a urine analysis device, as shown and described.

DESCRIPTION

FIG. 1 is a back side, left perspective view of our design; FIG. 2 is a front side, right perspective view of the design; FIG. 3 is a back view of the design; FIG. 4 is a front view of the design; FIG. 5 is a left view of the design; FIG. 6 is a right view of the design; FIG. 7 is a top view of the design; FIG. 8 is a bottom side view of the design; and, FIGS. 9-10 are the views of FIGS. 1-2 showing an example of the design arranged for sampling and analyzing urine. Any broken lines show portions of or parts associated with the urine analysis device design that form no part of the claim.
